C. E. ROWE

WINDOW SHADE GUIDE

Filed Feb. 18, 1924

FIG. 1

FIG. 2

FIG. 3

FIG. 4

INVENTOR,
Charles E. Rowe,
BY
Howard J. Smith,
His ATTORNEY

UNITED STATES PATENT OFFICE.

CHARLES E. ROWE, OF NEAR DAYTON, OHIO.

WINDOW-SHADE GUIDE.

Application filed February 18, 1924. Serial No. 693,460.

To all whom it may concern:

Be it known that I, CHARLES E. ROWE, a citizen of the United States, residing near the city of Dayton, in the county of Montgomery and State of Ohio, have invented certain new and useful Improvements in Window-Shade Guides, of which the following is a specification.

This invention relates to new and useful improvements in window-shade guides.

It is one of the principal objects of my invention to provide for window shades, ferrule guides that may be easily applied to a pole to maintain the shade in a true and proper position during its up and down movement and thereby protect it from injury.

When a window shade is drawn up and down, it frequently occurs, where no guide is provided, that the shade will run diagonally into contact with the pole brackets, which will tear or unravel it. My guides, which are simple in construction and are easily applied to the pole, make the shade run true at all times, thus protecting it from injury when it is raised and lowered.

It is another object of my invention to provide a shade guide in the form of a split ferrule which may be easily adjusted along the pole to accommodate shades of different widths. It is also capable of another adjustment in its ability to conform to poles of different diameters. And by virtue of its open slot, it may be adjusted to fit shades already attached to poles.

It is still another object of my invention to provide for shades, a ferrule guide which contains in its flange portion opposite its open slot, a V-notch which permits the metal to act as a hinge to allow the ferrule to expand.

In the accompanying drawings, Figure 1 is a front elevational view of a window shade attached to a pole on which my ferrules are placed to guide the vertical movement of the shade. Figure 2 is a rear side view of the split ferrule, showing how the shade is secured thereto. Figure 3 is perspective view of the split ferrule, showing the V notch in its flange portion. And Figure 4 is a perspective view of a non-slotted ferrule.

Referring to the accompanying drawings, the numeral 1 designates a shade or curtain pole to which there is tacked or otherwise secured, the upper end of a blind or shade 2. 55 For the purpose of causing this shade to run true when it is raised and lowered, there is secured to the pole 1 two ferrules 3, 3. Each ferrule, while it may be integral as shown in Figure 4, is preferably provided 60 with a longitudinal slot 4 which extends, parallel with its axis, through its curved face and a wide integral flange 5 on its outer end. By virtue of the open slot 4, the ferrules may be applied to poles of different 65 diameters for adjustment along them to positions to snugly engage shades of different widths.

Diametrically opposite the open slot 4 in each ferrule, there is formed in its flange 5, 70 a V-notch 6 which permits the ferrule to be freely expanded without crimping or pinching the material of which it is made. This may be aluminum, brass, steel or other suitable material from which stampings are 75 easily formed. The V-notch thus provides an opening through which its sides are free to move toward each other when the slot 4 in the ferrule is widened. The notch thus permits the metal to act as a hinge to allow 80 the ferrule to expand without crimping it.

The ferrules are easily and firmly applied to the shade on the pole, by slipping the upper side edges of said shade through the open slots 4 in the ferrules to points where 85 the flanges 5 on the latter snugly engage the side edges of the shade. (See Figures 1 and 2.) Then, when the shade is raised or lowered, those flanges will act as guides to cause the shade to run straight so that there is no 90 danger of it contacting with the pole brackets or other projections that would tear or unravel it.

It will thus be seen that I have provided simple and efficient means that may be adjusted to blinds, shades or curtains of different widths on poles of varying diameters, to guide them aright when they are raised or lowered.

Having described my invention, I claim: 100

1. A guide for a shade attached to a pole, consisting of a split ferrule having a slotted

flange on one end, and adapted to be slipped over said pole until a side edge of the shade projects through its split portion into engagement with said flange for the purpose specified.

2. A guide for a shade attached to a pole, consisting of a ferrule having a flange on

one end and an axial opening extending through it and the flange, the latter being formed opposite said opening with a V notch 10 for the purpose specified.

In testimony whereof I have hereunto set my hand this 16th day of February, 1924.

CHARLES E. ROWE.
